1

This invention relates to mass spectrometers and to mass spectrometry. More specifically, the invention is directed to improvements in the method of stabilizing ion beams and to apparatus for carrying out the improved method.

A mass spectrometer is an analytical instrument for sorting and measuring ions. Ordinarily, it includes an ionization chamber in which molecules of the sample to be analyzed are bombarded with a stream of electrons to convert them into ions. The ions formed are expelled from the ionization chamber by one or more repeller electrodes and are propelled by so-called propelling or accelerating electrodes into and through an analyzer chamber. The analyzer chamber frequently takes the form of a curvilinear enclosure, say a tube. During passage through the chamber, the heterogeneous beam of ions is subjected to a transverse electrical or magnetic field, or both, to separate it into separate diverging ion beams, each of which is composed of ions of a given mass-to-charge ratio which differs from the mass-to-charge ratio of the ions forming the other beams. The diverging beams may be successively focussed through an exit or resolving slit in a terminal electrode onto a collector electrode. Alternatively, a single one of the ion beams may be continuously focussed on the resolving slit to the exclusion of the other beams. In either event, the focussing of the ion beam or beams is achieved by adjustment of the potential applied to the accelerating electrodes. The current produced by ion discharge at the collector electrode is indicative of the amount of ions in the particular beam and hence, constitutes a measure of the partial pressure of the molecules (from which the ions were derived) in the sample being analyzed.

As indicated above, it may be expedient to focus the mass spectrometer on a single mass peak or step-wise on two or more mass peaks rather than sweeping the diverging ion beams successively across the resolving slit. Such a "fixed focus" instrument is used for continuous monitoring where a continuous concentration of a single constituent in a sample stream is sought, in leak detection where the presence of an added contaminant is detected as it appears in the atmosphere surrounding a vessel under investigation, and generally under any circumstances in which a single component or a pre-selected group of components is to be measured.

For accurate analysis with a fixed-focus mass spectrometer, it is important that the particular ion beam under investigation be at all times centered on the resolving slit. Any appreciable de-

2

flexion of the subject beam from a centered position will affect the apparent intensity of the beam and hence, result in erroneous analysis. Since the factors which govern the position of the beam are in a typical instrument, the transverse magnetic field and the accelerating voltage, deviation of either of these variables from a pre-selected fixed value will result in displacement of the beam from a centered position.

It has been proposed to stabilize the accelerating voltage against deviations from a pre-selected value by means of a voltage-dropping network wherein a fraction of the accelerating voltage is compared with the voltage output of a standard cell. Any variation in proportionality between the fraction and the standard voltage may be balanced automatically by a servo-motor or other means acting on the voltage source supplying the accelerating electrodes. However, the accuracy of such a system depends upon a resistance divider network, the long-term stability of which is questionable. Moreover, the possibility of loss of focus due to temperature sensitivity of the magnetic field, variations in power supply to an electromagnet, or aging of a permanent magnet is in no way accounted for in such a voltage-dropping network.

I have developed a method for holding a given ion beam centered on the resolving slit which automatically compensates for fluctuations in the accelerating voltage and variations in the strength of the magnetic field. The invention contemplates in a method of mass spectrometry which comprises ionizing a sample to be analyzed, propelling the ions by means of a D. C. accelerating potential into an analyzer region, subjecting the ions in the analyzer region to a transverse magnetic field to separate them into individual ion beams, focussing one of said ion beams through a resolving slit, discharging the beam passing through the resolving slit, and measuring the current developed by discharging of the beam, the improvement comprising superimposing on the D. C. accelerating potential an A. C. component to cause the ion beam to oscillate transversely with respect to the resolving slit, detecting deviation of the mean position of the oscillating beam from the center of the resolving slit and adjusting the accelerating potential to maintain said mean position centered in said resolving slit.

The invention also includes one form of apparatus for carrying out this method although other means for carrying out the method are possible. In its preferred form, the invention comprises in a mass spectrometer having an analyzer

chamber, ionization chamber, accelerating electrodes, a source of D. C. voltage connected to develop an accelerating potential on the accelerating electrodes, means for establishing a transverse magnetic field in the analyzer chamber, a collector electrode, and a terminal electrode having a resolving slit through which an ion beam is focussed on the collector electrode, the combination comprising means for impressing an A. C. component on the accelerating electrodes to oscillate the ion beam transversely with respect to the resolving slit, and means for varying the D. C. voltage applied from said source to the accelerating electrodes when the A. C. signal due to oscillation of the ion beam has the same fundamental frequency as the A. C. beam modulating component.

The invention will be more clearly understood by reference to the following detailed description taken in relation to the accompanying drawing in which:

Fig. 1 is a diagram of a mass spectrometer in accordance with the invention;

Figs. 2, 2A and 2B are charts showing, respectively, the results in terms of collector electrode output when a given ion beam is oscillated about a centered position on the resolving slit, when the given ion beam is oscillated about a widely decentered position, and when the given ion beam is oscillated about a slightly decentered position with respect to the slit where the amplitude of oscillation in each case is appreciably greater than the width of the resolving slit; and

Figs. 3 and 3A are charts showing, respectively, the results in terms of collector electrode output when a given ion beam is oscillated about a centered position on the resolving slit and when the given ion beam is oscillated about a decentered position with respect to the slit where the amplitude of oscillation in each case is only slightly greater than the width of the resolving slit.

The mass spectrometer shown diagrammatically in Fig. 1 includes a pair of accelerating electrodes 10, 11 and a repeller electrode 12. Ions are formed by an electron beam traversing the space between the repeller electrode and the first accelerating electrode 10 and are expelled from this region through a slit 10A in the accelerating electrode by application of a positive potential to the repeller electrode. The expelled ions are accelerated between the electrodes 10 and 11 and are discharged from a slit 11A in the second electrode by means of a potential impressed between the two accelerating electrodes.

The repelling and accelerating voltages are applied to the electrodes from a voltage supply circuit 14 including a D. C. source 15 connected in series with a slidewire resistor 16. The resistor 16 is tapped by slider 17 connected to a resistor 18. One end of the resistor 18 is connected to the positive side of the D. C. source 15 and is grounded at 20 adjacent the connected end. A lead 22 connects the repeller electrode to resistor 18 on the positive side of ground 20 and leads 23, 24 connect the two accelerating electrodes to spaced points on the resistor 18 on the negative side of ground 20. This arrangement represents a conventional voltage supply circuit for a fixed-focus mass spectrometer wherein any change in the voltage delivered from the source or applied across resistor 18 results in proportionate change in the voltages applied to the two accelerating electrodes.

The ions issuing from the second accelerat-

ing electrode 11 are caused to pursue a curved path as indicated by ion beam 26, the curved path being produced as the result of a transverse magnetic field established by magnet 27. The magnet 27 may be an electro-magnet or a permanent magnet, as desired. A terminal electrode 30 is placed in the path of the ion beam, say after it has travelled through a 180° arc, and is provided with a resolving slit 31 through which a single beam of given mass-to-charge ratio may be focussed. A collector electrode 32 is disposed behind the terminal electrode and ions passing through the resolving slit 31 impinge on the collector electrode and are discharged to produce a current proportional to the number of ions in the beam. The collector electrode is electrically connected to a D. C. amplifier 34 which amplifies the discharged signal and feeds it to a sensing means 36 which may be a recorder or other sensing device. To this point the operation of the mass spectrometer of Fig. 1 is typical of so-called fixed-focus instruments.

In accordance with the present invention, a source 38 of A. C. voltage is coupled through a switch 38A and a transformer 39 to the D. C. voltage supply circuit to superimpose on the D. C. voltage applied to the accelerating electrodes a comparatively small A. C. component of a frequency ω . An A. C. amplifier 40 is connected through a switch 42 to the collector electrode 32 so that the A. C. and D. C. amplifiers can be alternately connected to receive the discharge current developed at the collector electrode.

This represents preferred construction at the present state of the art, although it is perfectly possible to use a single amplifier for both the A. C. and D. C. signals or to have both amplifiers permanently connected to the ion collector, as will be evident to one skilled in this art.

Oscillation of the ion beam about a centered position and with an amplitude greater than the width w of the resolving slit, shifts the highest intensity portion of the beam out of position so that it strikes the terminal electrode 30 instead of passing through the resolving slit to discharge on the collector electrode. When the beam shifts back to the centered position, the discharge signal is again at maximum intensity. Thus, an A. C. component appears in the collector electrode output when the beam is oscillated. The frequencies and phases of the various components into which the A. C. signal may be resolved depends upon the mean position of the beam, provided only that the amplitude of oscillation is greater than w , as will appear hereinafter. Since oscillation of the beam reduces the average intensity on the collector electrode, it is preferred practice to oscillate it only while the collector electrode is connected to the A. C. amplifier 40 through switch 42. For this reason, switches 42 and 38A are ganged so that an A. C. component is impressed on the accelerating electrodes from source 38 only when the A. C. amplifier is connected to receive the output of the collector electrode.

A reversible motor 44 is mechanically coupled to the slider 17 of the voltage supply circuit so that operation of the motor will adjust the position of slider 17 with respect to the slidewire 16. One coil 44A of the motor is connected to the A. C. source 38 and the other coil 44B of the motor is connected to the output of the A. C. amplifier 40.

In using the apparatus of Fig. 1, switch 42 is conveniently a timing switch which connects

the collector electrode to the D. C. amplifier for a great majority of the time and to the A. C. amplifier 40 for a few seconds out of every 10 or 15 minutes.

The operation of the apparatus can be best described with relation to the diagrams of Figs. 2 and 3. Figs. 2, 2A and 2B are graphs of the current developed at the collector electrode by an ion beam oscillating across the resolving slit with an amplitude considerably greater than the width w of the resolving slit, the several figures showing the mean position of the beam on the slit axis, to the side of the slit and in an intermediate position, respectively. Figs. 3 and 3A depict the current developed at the collector electrode by an oscillating beam centered on the slit, and slightly decentered, respectively, where the amplitude of beam oscillation is just greater than the width w of the resolving slit.

When switch 42 is connected to the D. C. amplifier 34, the ion beam is not oscillated and the setting of tap 17 remains fixed. Periodically, say every 15 minutes, switch 42 is adjusted to connect the collector electrode to the A. C. amplifier, at which time any variation in accelerating voltage or magnetic field strength is compensated by appropriate adjustment of the slider 17 so that the preselected ion beam will remain centered on the resolving slit 31.

Assuming that switch 42 is connected to the A. C. amplifier 40 and that A. C. source 38 is connected in the voltage supply circuit through switch 38A, as shown in Fig. 1, and that the ion beam 26 is perfectly centered on the resolving slit 31, the situation depicted in Fig. 2 will pertain when the amplitude of oscillation is appreciably greater than w . The collector electrode output is shown as pips 46, 46A, 46B, etc., corresponding to the periods when the ion beam 26 is passing through the resolving slit. The oscillating ion beam and resolving slit are shown beneath the output curve of the collector electrode. At the zero position of the beam, considering the beam oscillation responsive to the A. C. component impressed on the accelerating electrode, it is perfectly centered on the resolving slit and a signal is applied to the A. C. amplifier and through the amplifier to coil 44B of motor 44. A quarter of a cycle later the beam 26 has moved to the left of the slit and no signal is applied to the amplifier. A quarter of a cycle later the beam returns to the center of the slit and the signal 46A is developed. The oscillation of the beam with respect to the slit throughout two complete cycles is shown in the Fig. 2. The first Fourier component of the discharge signal is superimposed on the graph. It will be seen that the fundamental frequency of this component is 2ω where the frequency of the voltage output of the source 38 is ω since there are two equally spaced pips developed for each cycle as reflected in the oscillation of the ion beam. Under these conditions, motor 44 will not be operative since the frequency of the signal applied to coil 44B is twice the frequency of the signal applied to coil 44A from source 38.

A similar graph is shown in Fig. 2A wherein the mean beam position lies outside the resolving slit. Thus, as shown at the extreme left of Fig. 2A, the zero position of the ion beam is to the left of the resolving slit 31. Oscillation of the beam carries it into the resolving slit but the mean position is so far off center that the beam does not sweep across the slit. Each time the beam sweeps into the slit, a signal represented

5 by the pips 50, 50A, etc., is developed at the collector electrode, the duration of each signal depending on the time the beam is focussed on the slit. In this instance, the first Fourier component is seen to have a fundamental frequency ω . When this signal is applied from the A. C. amplifier to the motor coil 44B, being of the same frequency as the A. C. signal applied to coil 44A, the motor will be energized, moving slider 17 in the appropriate direction to return the beam to a mean centered position. If the beam is decentered to the right of the resolving slit, a signal similar to that shown in the graph of Fig. 2A, but of opposite phase, is developed. When such a signal is applied to the motor coil 44B, the motor will be energized in the opposite direction to accomplish the necessary adjustment of slider 17.

10 In Fig. 2B, the mean position of the oscillating ion beam lies off center on the exit slit, i. e., intermediate the positions shown in Figs. 2 and 2A. Again a signal, represented by pips 52, 52A, etc., is developed at the collector electrode throughout each period that the oscillating beam falls on the slit. Where the beam decentering is sufficiently small that the beam sweeps across the slit, the pattern of the discharge signal differs from that developed when the beam is decentered to such an extent that it sweeps only a part of the slit (Fig. 2A). However, it will be observed that the first Fourier component of the discharge current as per Fig. 2B has a fundamental frequency ω , and hence, this signal applied to the motor coil will operate the motor in the same manner as the signal developed under the conditions shown in Fig. 2A.

20 The exact appearance of the current pips shown in the drawings will depend on the relative magnitude of the slit width, the beam width, and the oscillation amplitude. As an example of the variability of such appearance, Figs. 3 and 3A show a mode of operation in which the beam is narrower than the slit and the modulation amplitude is just large enough to move the beam to the slit edge. Comparison of Figs. 2 and 2B with Figs. 3 and 3A will make it evident that although the pip appearance is very different in the two cases, the A. C. signals developed by a centered or decentered beam are essentially identical with the corresponding cases of Fig. 2.

30 A significant feature of the invention, therefore, is that no matter how small the focussing error may be, the signal developed at the collector electrode by an oscillating ion beam will have at least a first Fourier component of a frequency identical to the frequency of oscillation of the beam so long as the amplitude of oscillation is at least equal to the width of the resolving slit. On the other hand, when the beam is centered, the first Fourier component of the signal developed by an oscillating beam will have a frequency of twice the frequency of beam oscillation. This means that a correction factor will be applied to the accelerating voltage even when loss of focus is so small as to produce only a negligible error in the analysis.

40 The method and apparatus described has the important advantage of correcting for all defects, contributing to undesired shift of the preselected ion beam. A high degree of sensitivity is not necessary in the A. C. amplifier since the device can be adjusted to sense on a strong peak. Thus, if the particular peak of interest is extremely weak, the switch 42 can be connected to the voltage supply circuit in such a fashion

that switching from a D. C. amplifier to the A. C. amplifier will at the same time alter the accelerating voltage to focus a stronger mass peak on the resolving slit. This can be accomplished, for example, by means of a stepper switch (not shown) in the voltage supply circuit operated responsive to the position of switch 42. Thus, it is not essential that the instrument "center" itself on the particular peak being analyzed since any of the factors contributing to decentering of a given peak will normally contribute to decentering of any other given peak.

Constancy of amplification in the A. C. amplifier is also not a problem provided only that the gain remains large enough to drive the motor. The system balances to a null with respect to the fundamental component of the A. C. amplifier output so that variation in gain within the range sufficient to operate the motor can be tolerated. Furthermore, motors can be obtained commercially which automatically discriminate against noise and extraneous frequencies which, therefore, do not interfere with the operation of the apparatus so long as they are not present in sufficient amounts to jam the motors by over-damping.

The method and apparatus is simpler, less expensive, and more certain than any means heretofore proposed for holding a mass spectrometer on the top of a pre-set peak or a group of peaks by attempting to achieve a high degree of long-term stability in the magnet and in the power supply.

Although the invention has been described with particular reference to a continuous monitor instrument in which a single mass peak is of interest, it is not so limited. In any operation wherein the mass peaks are focussed step-wise on the resolving slit, the present invention is of value.

Furthermore, application of the invention is not limited to the particular apparatus illustrated. It is entirely practical to produce the necessary oscillation of the ion beam by means other than impression of an A. C. voltage on the accelerating electrodes. For example, auxiliary electrodes arranged transversely with respect to the path of ion travel will induce the same type of oscillation when energized with an A. C. voltage. Alternatively, the magnetic field may be varied in a rhythmic manner to accomplish the same purpose. At the same time, the correction applied by motor 44, or by other means sensitive to the Fourier component of the collector electrode output of the frequency of beam oscillation, is not restricted to adjustment of the accelerating potentials. Variation in the magnetic field strength or an auxiliary field developed by auxiliary deflecting electrodes will also accomplish the desired adjustment of the beam.

The method of the invention, therefore, involves oscillating the ion beam in any desired manner and adjusting a beam focussing field, whether it be a lateral or transverse electric field or a transverse magnetic field, responsive to the Fourier component of collector electrode output having the same frequency as the oscillation frequency of the ion beam.

I claim:

1. In mass spectrometry involving ionizing a sample to be analyzed, propelling the ions by means of a D. C. accelerating potential into an analyzing zone as a heterogeneous beam, subjecting the ions in the analyzing zone to a trans-

verse magnetic field to separate the heterogeneous beam into a plurality of diverging beams, focussing one of said beams on an outlet slit in the analyzing zone, discharging the ion beam passing through the outlet slit, and measuring the current developed by discharge of the beam, the improvement which comprises superimposing on the D. C. accelerating potential an A. C. component to cause the ion beam to oscillate transversely with respect to the outlet slit and at an amplitude such that the beam will impinge on an edge of said outlet slit at least once in each cycle of oscillation, detecting the mean position of the oscillating beam, and adjusting the accelerating potential to maintain said mean position centered on said outlet slit.

2. In mass spectrometry involving ionizing a sample to be analyzed, propelling the ions by means of a D. C. accelerating potential into an analyzing zone as a heterogeneous beam, subjecting the ions in the analyzing zone to a transverse magnetic field to separate the heterogeneous beam into a plurality of diverging beams, focussing one of said beams on an outlet slit in the analyzing zone, discharging the ion beam passing through the outlet slit, the improvement which comprises periodically superimposing on the D. C. accelerating potential an A. C. component to cause the ion beam to oscillate transversely with respect to the outlet slit and at an amplitude such that the beam will impinge on an edge of said outlet slit at least once in each cycle of oscillation, detecting the mean position of the oscillating beam, and adjusting the accelerating potential to maintain said mean position centered on said outlet slit.

3. In mass spectrometry involving ionizing a sample to be analyzed, propelling the ions by means of a D. C. accelerating potential into an analyzing zone as a heterogeneous beam, subjecting the ions in the analyzing zone to a transverse magnetic field to separate the heterogeneous beam into a plurality of diverging beams, focussing one of said beams on an outlet slit in the analyzing zone, discharging the ion beam passing through the outlet slit, and measuring the current developed by discharge of the beam, the improvement which comprises periodically superimposing on the D. C. accelerating potential an A. C. component to cause the ion beam to oscillate transversely with respect to the outlet slit and at an amplitude such that the beam will impinge on an edge of said outlet slit at least once in each cycle of oscillation, detecting the mean position of the oscillating beam, and adjusting the accelerating potential to maintain said mean position centered on said outlet slit.

4. In mass spectrometry involving ionizing a sample to be analyzed, propelling the ions by means of a D. C. accelerating potential into an analyzing zone as a heterogeneous beam, subjecting the ions in the analyzing zone to a transverse magnetic field to separate the heterogeneous beam into a plurality of diverging beams, focussing one of said beams on an outlet slit in the analyzing zone, discharging the ion beam passing through the outlet slit, and measuring the current developed by discharge of the beam, the improvement which comprises periodically superimposing on the D. C. accelerating potential an A. C. component to cause the ion beam to oscillate transversely with respect to the outlet slit so that the discharge signal of said beam

includes an A. C. component, and adjusting the accelerating potential responsive to the A. C. component of said discharge signal when said component is of the same frequency as the A. C. component superimposed on the accelerating potential to maintain the mean position of the oscillating beam centered on said outlet slit.

5. In mass spectrometry involving ionizing a sample to be analyzed, propelling the ions by means of a D. C. accelerating potential into an analyzing zone as a heterogeneous beam, subjecting the ions in the analyzing zone to a transverse magnetic field to separate the heterogeneous beam into a plurality of diverging beams, focussing one of said beams on an outlet slit in the analyzing zone, discharging the ion beam passing through the outlet slit, and measuring the current developed by discharge of the beam, the improvement which comprises periodically superimposing on the D. C. accelerating potential an A. C. component of sufficient magnitude to cause the ion beam to oscillate transversely with respect to the outlet slit with an amplitude greater than the width of the ion slit so that the discharge signal of said beam includes an A. C. component and adjusting the accelerating potential responsive to the A. C. component of said discharge signal when said component is of the same frequency as the A. C. component superimposed on the accelerating potential to maintain the mean position of the oscillating beam centered on said outlet slit.

6. In mass spectrometry involving ionizing a sample to be analyzed, propelling the ions by means of a D. C. accelerating potential into an analyzing zone as a heterogeneous beam, subjecting the ions in the analyzing zone to a transverse magnetic field to separate the heterogeneous beam into a plurality of diverging beams, focussing one of said beams on an outlet slit in the analyzing zone, discharging the ion beam passing through the outlet slit, and measuring the current developed by discharge of the beam, the improvement which comprises periodically superimposing on the D. C. accelerating potential an A. C. component to cause the ion beam to oscillate transversely with respect to the outlet slit so that the discharge signal of said beam includes an A. C. component, and automatically adjusting the accelerating potential responsive to the A. C. component of said signal when said component is of the same frequency as the A. C. component superimposed on the accelerating potential to maintain the mean position of the oscillating beam centered on the outlet slit.

7. In mass spectrometry involving ionizing a sample to be analyzed, propelling the ions by means of a D. C. accelerating potential into an analyzing zone as a heterogeneous beam, subjecting the ions in the analyzing zone to a transverse magnetic field to separate the heterogeneous beam into a plurality of diverging beams, focussing one of said beams on an outlet slit in the analyzing zone, discharging the ion beam passing through the outlet slit, and sensing the current developed by discharge of the beam, the improvement which comprises periodically altering the accelerating potential by a given increment to focus a different ion beam on the outlet slit, superimposing on the altered accelerating potential an A. C. component to cause said different beam to oscillate transversely with respect to the outlet slit so that the discharge signal of said different beam includes an A. C. component, adjusting the altered accelerating poten-

tial responsive to the A. C. component of said signal when said component is of the same frequency as said superimposed A. C. component to maintain the focus of said different ion beam on the center of the outlet slit, and altering the adjusted accelerating voltage by said given increment to again focus said one of said ion beams on the outlet slit.

8. In a mass spectrometer having an analyzer chamber, ionization chamber, accelerating electrodes, a source of D. C. voltage connected to impress an accelerating potential on the accelerating electrodes for propelling ions from the ionization chamber into and through the analyzer chamber, means for establishing a transverse magnetic field in the analyzer chamber, a collector electrode, and a resolving electrode having a resolving slit through which an ion beam is focussed on the collector electrode, the combination comprising means for impressing an A. C. voltage component on the accelerating electrodes to oscillate the ion beam transversely with respect to the resolving slit, means for developing an A. C. signal at said collector electrode responsive to oscillation of the ion beam and means for varying the D. C. voltage applied from said source to the accelerating electrodes when said A. C. signal has the same fundamental frequency as said A. C. component.

9. In a mass spectrometer having an analyzer chamber, ionization chamber, accelerating electrodes, a source of D. C. voltage connected to impress an accelerating potential on the accelerating electrodes for propelling ions from the ionization chamber into and through the analyzer chamber, means for establishing a transverse magnetic field in the analyzer chamber, a collector electrode, and a resolving electrode having a resolving slit through which ions pass to the collector electrode, the combination comprising means for impressing an A. C. voltage component on the accelerating electrodes, and means operable responsive to the output of the collector electrode having the same frequency as said A. C. component to vary the D. C. voltage applied from said source to the accelerating electrodes.

10. In a mass spectrometer having an analyzer chamber, ionization chamber, accelerating electrodes, a source of D. C. voltage connected to impress an accelerating potential on the accelerating electrodes for propelling ions from the ionization chamber into and through the analyzer chamber, means for establishing a transverse magnetic field in the analyzer chamber, a collector electrode, and a resolving electrode having a resolving slit through which ions pass to the collector electrode, the combination comprising means for impressing an A. C. voltage component on the accelerating electrodes, an A. C. amplifier connected to the collector electrode, means operable responsive to the output of the A. C. amplifier when said output is at the same frequency as said A. C. component to vary the D. C. voltage applied from said source to the accelerating electrodes.

11. In a mass spectrometer having an analyzer chamber, ionization chamber, accelerating electrodes, a source of D. C. voltage connected to impress an accelerating potential on the accelerating electrodes for propelling ions from the ionization chamber into and through the analyzer chamber, means for establishing a transverse magnetic field in the analyzer chamber, a collector electrode, and a terminal electrode hav-

ing a resolving slit through which ions pass to the collector electrode, the combination comprising a source of A. C. voltage connected to impress an A. C. voltage component on the accelerating electrodes, an A. C. amplifier connected to the collector electrode, adjusting means for varying the D. C. voltage applied from said source to the accelerating electrodes, a motor mechanically connected to control said adjusting means, one coil of said motor being connected to said source of A. C. voltage and another coil of the motor being connected to the output of said A. C. amplifier so that the motor is actuated only when the output of said amplifier has a component of the same frequency as the A. C. voltage.

12. In a mass spectrometer having an analyzer chamber, ionization chamber, accelerating electrodes, a D. C. voltage supply circuit connected to impress an accelerating potential on the accelerating electrodes for propelling ions from the ionization chamber into and through the analyzer chamber, means for establishing a transverse magnetic field in the analyzer chamber, a collector electrode, and a terminal electrode having a resolving slit through which ions pass to the collector electrode, the combination comprising a source of A. C. voltage connected to said D. C. voltage supply circuit to impress an A. C. voltage component on the accelerating electrodes, an A. C. amplifier connected to the collector electrode, a first switch means for disconnecting the source of A. C. voltage from said supply circuit, second switch means for disconnecting the A. C. amplifier from the collector electrode, means for simultaneously operating the first and second switch means, adjusting means for varying the voltage applied from said supply circuit to the accelerating electrodes, a motor mechanically connected to con-

trol said adjusting means, one coil of the motor being connected to the source of A. C. voltage and another coil of the motor being connected to said A. C. amplifier so that the motor is actuated only when the output of said amplifier has a component of the same frequency as the A. C. voltage.

13. In mass spectrometry involving ionizing a sample to be analyzed, subjecting the ions to a combination of electric and magnetic fields to separate the ion beam into a plurality of divergent beams each having a characteristic mass-to-charge ratio, and passing one such divergent beam through a resolving slit onto a collector, the improvement which comprises causing one of said beams to oscillate across the resolving slit and sensing on the Fourier component of the collector current signal whose frequency is the same as the frequency with which the beam is oscillated across the slit, and adjusting the position of the beam with respect to the slit responsive to said Fourier component.

14. In a mass spectrometer having an analyzer chamber, ionization chamber, accelerating electrodes for propelling ions from the ionization chamber through the analyzer chamber, means for establishing a transverse electric field across the analyzer chamber, a collector electrode and a terminal electrode preceding the collector electrode and having a resolving slit therein, the combination comprising means for oscillating an ion beam with respect to said resolving slit, and means associated with the collector electrode and operable responsive to uncentered oscillation of the beam to vary the beam focus to restore centered oscillation of the beam.
